UNITED STATES PATENT OFFICE.

WALther DALHEIMER, OF EINDHOVEN, NETHERLANDS, ASSIGNOR TO N. V. PHILIPS' GLOEILAMPENFABRIEKEN, OF EINDHOVEN, NETHERLANDS, A LIMITED LIABILITY COMPANY OF THE NETHERLANDS.

FEEDING MECHANISM.

Application filed December 31, 1926, Serial No. 158,397, and in the Netherlands February 18, 1926.

This invention has reference to apparatus for feeding and cutting helices in pieces with any required number of windings.

It is often desirable to divide the said helices into such parts as to obtain helices with a broken number of windings. Thus, for example, it may be necessary in the manufacture of discharge tubes to use helices of $16\frac{1}{2}$ or $17\frac{1}{4}$ windings.

According to the invention the apparatus comprises in combination a feeding device for the helices and cutting means, said feeding device and cutting means being rotatable with respect to each other. The cutting device may rotate around the helices; it is also possible to have the cutting device stationary provided and to impart to the helices a rotary movement.

The said apparatus will be more clearly understood by reference to the accompanying drawings. In the said drawings:

Figure 1 is an elevation of apparatus according to the invention, in which the cutting device for sake of clearness is omitted.

Figure 2 is a cross-section taken on the line II-II of Figure 1 in which the cutting device is indicated.

Figure 3 is a front view in detail of the cutting device.

Referring to Figure 1 a frame 1 has mounted on it a pedestal 2. In this pedestal is mounted a sleeve 3 in which a shaft 6 is adapted to rotate and to the periphery of which are secured ball-bearings 4 and 5 for supporting a rotary body 7. The shaft 6 which is provided with a central bore 13 has mounted on it a head 10 on which are arranged brackets 11 and 12 for supporting rolls 14 and 15. The roll 15 is mounted on a lever 16 pivoted at 17 and a spring 18 tends to force said roll against the roll 14. The roll 14 is keyed to a shaft 19 which has in addition gears 20 and 21 rigidly attached to it. The roll 15 is adapted to rotate by means of a shaft 22 and moreover it is rigidly coupled to a pinion 23 which is fast on the same shaft. By the spring 18 said pinion is kept in engagement with the gear 20. When therefore the gear 21 is being actuated both the roll 14 and the roll 15 are

operated. The gear 21 forms part of a spiral gearing of which the worm 26 which is fast on the body 7 constitutes the driving element so that a rotation of the body 7 will cause the gear 21 to rotate. In order that the body 7 may be rotated it is provided with a toothed part 9 which is adapted to be rotated by any gear driving.

As described hereinbefore the shaft 6 has mounted on it the rolls 14 and 15. The other end of the said shaft has fast on it a gear 8 which is in engagement with a gear 28 mounted on a shaft 27. When the gear 8 is not rotated the head 10 will not shift relatively to the sleeve 3 and the rolls 14 and 15 will therefore be stationary in a determined position, for example in the vertical position shewn in Figure 1. By reason, however, of a rotation being imparted to the shaft 27, the gear 8 will rotate and in addition to the movement around their own axes, the rolls 14 and 15 will receive a rotation around the center line of the sleeve 3.

The shaft 6 is provided with a central bore 13 for the passage of the helix which is to be fed. In connection therewith a guide 31 is mounted which is opened out in close relation to the point of contact of the two rolls. When a helix is passed through the bore 13 and the guide 31 it will be gripped by the rolls 14 and 15 which due to their rotary movement, will feed the helix through the guide 51 of the cutting device (Figures 2 and 3). In order to grip the helix in the right way the rolls 14 and 15 are provided with grooves that correspond to the windings of the helix. On a rotary movement being imparted to a pulley 33 secured to the shaft 27 the gear 8 will start rotating and as a result the rolls 14 and 15 will receive a rotary movement about the centre lines of the shaft 6 or the sleeve 3.

In operation a helix will be fed along the cutting device which is formed by the guide 51 and the cutter 50. Due to the rotation of the helix it will be possible to cut helices with a broken number of windings. It is, for instance, possible by a suitable drive of the gear 9 and the shaft 27 to have the helix

be pushed forwardly ten windings and to give the shaft 6 simultaneously a quarter of a revolution. If now the cutter 50 severs the helix at every ten windings, the helices 5 will have either $9\frac{3}{4}$ or $10\frac{1}{4}$ windings. It is evident that by a combination of these two movements a helix of any number of windings can be obtained.

What I claim is:—

- 10 1. Apparatus for feeding and cutting helixes in pieces with any required number of windings comprising rolls adapted to feed the helix and means to impart a rotation to said rolls around the centre line of the helix in addition to the rotary movement of said rolls around their axis and cutting means adapted to cooperate with the said feeding means.
- 15 2. Apparatus for feeding and cutting helixes in pieces with any required number of windings comprising rolls and a centrally bored rotary shaft, said rolls being mounted on said shaft, a body rotating around said shaft, for imparting rotary movement to said rolls around their own axis and cutting means being adapted to cooperate with said rolls.
- 20 3. Apparatus for feeding and cutting helixes in pieces with any required number of windings comprising rolls and a centrally bored rotary shaft, said rolls being mounted on said shaft, a body rotating around said shaft, for imparting rotary movement to said rolls around their own axis, a worm gear being coupled to said rolls, said body being provided with spiral teeth which engage said worm gear and a cutting device adapted to cooperate with said rolls.
- 25 4. Apparatus for feeding and cutting helixes in pieces with any required number of windings comprising a feeding device for the helix and cutting means, said device and said means being rotatable with respect to each other, the axis of rotation being the centre line of the helix.

In testimony whereof I affix my signature, at the city of Eindhoven, this 15th day of December, 1926.

50 WALTHER DALHEIMER.
